(57) **CLAIM**

The ornamental design for an inhaler, as shown and
described.

DESCRIPTION

FIG. 1 is a front elevation view of an inhaler;

FIG. 2 is a right elevation view thereof;

FIG. 3 is a rear elevation view thereof;

FIG. 4 is a left elevation view thereof;

FIG. 5 is a bottom plan view thereof;

FIG. 6 is a top plan view thereof;

FIG. 7 is a perspective view from the top, front and left
corner thereof;

FIG. 8 is a perspective view from the bottom, front and right
corner thereof; and,

FIG. 9 is a perspective view from the top, front and right
corner thereof.

The broken lines in the drawings illustrate portions of the
inhaler that form no part of the claimed design.

1 Claim, 9 Drawing Sheets
